UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

TREATING APPARATUS.

Application filed September 8, 1923. Serial No. 661,683.

This invention relates to apparatus for treating shoes in process of manufacture and more particularly to apparatus for softening the upper leather and stiffening members to facilitate shaping them to the lasts. According to most approved manufacturing methods now being practised it is customary to soften the toe end of an assembled shoe prior to the pulling-over operation and to perform a second softening operation, after the pulling-over operation, to render the toe end limp and pliant for the lasting operation. Many features of the present invention hereinafter described are capable of use in either of the softening operations above mentioned, but since the illustrated apparatus is designed more especially for the second softening operation the invention will be described in terms relating to the operation by which a pulled-over shoe is softened for lasting.

The most effective softening treatment for the purpose above stated consists in subjecting the work to the action of moderate heat and moist vapor. Many types of apparatus heretofore used for this purpose have been objectionable for one reason or another. For example, some require too much time after a period of non-use to acquire a sufficiently effective working condition, some entail an operating cost too great to be economical, some discharge excessive quantities of vapor, and some overheat the shoes and scorch them because of faulty design or insufficient provision for regulation.

Accordingly an object of the invention is to provide improved treating apparatus having a relatively low operating cost, a rapid heating and vapor-producing capacity, and provision for quick regulation and complete control of the vapor output.

More specifically, an object is to provide an improved apparatus to generate the vapor with a high degree of efficiency and without possibility of overflowing. In this respect a feature of the invention consists in an organization comprising a boiler of small capacity and a communicating gravity-feed water-reservoir to hold a relatively large supply of water in equilibrium when the boiler is not functioning, and further, in a restricted communicating waterway the replenishing capacity of which is preferably less than commensurate with the vaporizing

capacity of the boiler. A feature closely related to this consists in restricting the water-space of the boiler to an exceedingly small area. One result of these features is that the initial accumulation of water in the boiler may be wholly dissipated by vaporization within a few minutes after starting the operation of the boiler; and thereafter the operation is that of a flash-boiler. Another result is that when the heating agent is turned off the boiler and the reservoir maintain the water in equilibrium as soon as enough water has flowed through the replenishing connection to raise the level in the boiler to that in the reservoir. This anti-flooding feature does away with the necessity of disturbing the regulating valve or otherwise turning off the water.

Another feature consists in the construction of the flash-boiler by which a high degree of efficiency is obtained. In the illustrated construction the boiler comprises an upstanding tubular outer shell and an upstanding core which, together, form a thin annular water-space in open communication with the atmosphere and having a depth as great as, if not greater than, that of the water-reservoir but having a minimum water capacity. The shape of the water-space is like that of a thin tube of considerable length and diameter. Preferably the vaporizing heat is developed in the core with or without supplemental heat developed elsewhere.

Loss of heat by conduction to the reservoir is prevented by arranging the boiler and reservoir apart from each other and providing a replenishing pipe so long and yet so small in cross-sectional area that its tendency to transmit heat is counteracted by the water flowing through it constantly in the opposite direction. Whatever heat is developed in this pipe is carried back to the boiler by the water and utilized, excepting a negligible quantity lost by radiation.

The invention consists further in a novel combination comprising a flash-boiler and a heat-radiating and heat-conducting element formed and arranged to spread the vapor laterally. This combination provides for supporting one heat-radiating element by the other and provides a compact assemblage designed to conserve the heat. As shown, the upper heat-radiating element

supports the flash-boiler, the latter being suspended by the aforesaid outer shell which is therefore heated not only by the core but also by the supporting element.

5 Still another feature consists in improved means for mounting the heated elements of the apparatus on a supporting base or stand without detracting appreciably from the heating efficiency of the apparatus. This
10 feature preferably comprises iron or steel connecting rods of considerable length to restrict the conduction of heat, but having short bends of 180 degrees to afford compactness of the assemblage.

15 Other features of the invention are hereinafter described and claimed and illustrated by the drawings.

In the drawings.

Fig. 1 is a front elevation partly in section of an apparatus embodying the invention in a form suitable to treat two shoes at once:

Fig. 2 is a vertical section in the planes indicated by line 2-2 of Fig. 1 and includes the forepart of a pulled-over shoe in position for treatment;

Fig. 3 is a perspective view partly in section of a portion of the metallic heat-radiating structure in which the treating chambers are formed; and

30. Fig. 4 is a horizontal section in the plane indicated by line 4-4 of Fig. 1.

The illustrated apparatus comprises a cast iron base or supporting structure 10 designed to stand on a bench and provided with legs 11 to form the stand. A cast iron heat-radiating structure 12 is supported by the structure 10 but preferably has no direct contact therewith because it is desirable to minimize the conduction of heat in that direction. Accordingly the structures 10 and 12 are connected by a pair of U-shaped iron or steel rods 13 which, though having a slight capacity to conduct heat, so far minimize the conduction thereof that the structure 12 is, to all intents and purposes, insulated from the structure 10 to conserve the heat in the structure 12. These connecting rods are anchored in bosses formed on the structure 10 and are secured by bolts 14. The rods also extend through bosses 15 formed on the heat-radiating structure 12, the latter being thus suspended and vertically adjustable relatively to the rods and provided with set-screws 16 to engage the rods.

60 The heat-radiating structure 12 is formed to provide two treating chambers 17 and 18 side by side as shown in Fig. 1, these chambers being separated by a partition 19 (see also Fig. 3). Each chamber has a back wall 20, an end wall 21, a bottom wall 22, and a top wall 23. The top wall is preferably adjustable to vary the area of the opening at the front of the chamber, and for this purpose it is preferably connected to the end 65

walls 21 by trunnions 24 one of which, the right-hand one in Fig. 1, is preferably a wing bolt adapted to clamp the top wall in any desired position. The structure 12 is formed with a double bottom to provide a vapor chamber 25, and the walls 22 are provided with holes 26 to emit the vapor from the chamber 25 to the treating chambers. Foraminous brass plates 27 are preferably arranged on the bottom walls 22 to equalize the distribution of vapor. The bottom of the structure 12 is also provided with chambers for the reception of electric heating units 28, these chambers being open at the back wall 20 for the insertion of the heating units.

Hot moist vapor at atmospheric pressure is supplied to the chamber 25 by a flash boiler comprising an upstanding cylindric tube or shell 30 and an upstanding cylindric heat-radiating core 31. These elements are both preferably made of cast iron, and are connected by bolts 32. A gasket 33 of any suitable material, for example copper or lead, provides a water-tight joint. The tube or shell 31 is open at the top and is supported by and hangs from the bottom of the structure 12, being fastened to the latter by bolts 34. The shell 30 and core 31 together form an upstanding tubular space or well of very small capacity in comparison to the surface area presented by the core. A chamber is formed in the core for the reception of an electric heating unit 36, said chamber being open only at the bottom for the insertion of the unit.

Electric conductors 37 lead from the units 36 and 28 to a switch 38 having a rotary operating knob 39. Although any preferred type of switch may be used I prefer one that has four positions, in one of which the current is turned off from all the units, in another of which the current is turned on with respect to the units 28, in another of which it is turned on with respect to all the units, and in the fourth of which it is turned off with respect to the units 28 but maintained with respect to the unit 36. It is thus possible to operate the heat-radiating element 12 without supplying any vapor, or to operate the vaporizer in conjunction with the heat-radiating element 12, or to operate the vaporizer without developing heat in the structure 12.

The base structure 10 is formed to provide a reservoir 40 for water to be vaporized, the connection between the reservoir and the water space of the vaporizer being designed to maintain thermal insulation of the vaporizer. The water flows by gravity from the reservoir through a small brass or copper pipe 41 and enters the bottom of the water-space formed by the heat-radiating core 31 and the surrounding shell 30. When the apparatus is not in operation

the water in the reservoir and that in the vaporizer are in equilibrium, but when the vaporizer is in operation it quickly evaporates all the surplus water therein because the maximum capacity of the pipe 41 is less than the vaporizing capacity of the heat-radiating core. Consequently, as soon as all the surplus water in the vaporizer has been vaporized the vaporizer operates as a flash-boiler and continues so to operate until the current is turned off. Under these conditions the heat developed in the core 31 maintains the water in the vaporizer considerably below its normal level and thus causes nearly the entire periphery as well as the top of the core to be exposed to the vapor. Both the shell 30 and the heated core 31 extend upwardly nearly to the level of the work, and the annular sheet of vapor surrounding the core, being constrained by the shell to flow along the core, is further heated by the core until it nearly reaches the work. These conditions insure a considerable increase in the temperature of the vapor above the initial temperature thereof. In consequence, the softening of the work is accomplished quickly but the quantity of moisture delivered to the work is very slight. Then, when the heat of the core 31 is too low to continue boiling, the equilibrium of the water will be restored but the vaporizer will not overflow because its upper portion is as high as the maximum water level of the reservoir.

Most of the heat that seeks to pass along the pipe 41 by conduction is carried back to the boiler by the water flowing to the latter and never reaches the coupling by which the pipe is connected to the reservoir.

A needle-valve 42 is provided to regulate the quantity of water that may flow through the supply pipe, said valve being screwed into a sleeve 43 to which the supply pipe is coupled. A hole 44 extending diametrically through the sleeve completes the communicating passageway.

The top of the reservoir is preferably open to facilitate filling excepting when it is covered by a movable work support 45 which is preferably made of wood. The work support is connected to the structure 10 by a hinge-rod 46 which extends through supporting ears 47. An adjusting screw 48 screwed into the structure 10 serves as a support for the front margin of the work support 45 and provides for adjusting the latter to various angles.

To guard against scorching the work the end walls 21, 21 and the partition 19 may be faced with strips 50 of wood or any other heat-insulating material.

The shoe indicated at 51 is one of the smaller sizes and accordingly the adjustable top wall 23 of the heating chamber is set at a relatively low position to restrict

the outlet from the treating chambers so that the vapor, instead of escaping too rapidly, will be retained in the chambers long enough to envelop the toes and thereby promote the efficiency of the apparatus. When it is desired to treat a larger shoe it would be preferable to raise the top wall 23 sufficiently to provide ample clearance for the instep portion, for otherwise the hot vapor escaping at that point might scorch the work.

Having thus described my invention, what I claim as new and desire to secure by Letters Patent of the United States is:

1. A treating apparatus comprising a flash-boiler and a water reservoir both open to the atmosphere and in communication with each other and arranged to hold the water in equilibrium when the boiler is not functioning, the vaporizing capacity of said boiler exceeding the maximum rate of flow of water from the reservoir to the boiler.

2. A treating apparatus comprising a tank for supplying water, an open well of relatively small capacity the top and bottom of which are respectively above and below the highest water level of said tank, means arranged to conduct water by gravitation from said tank to said well, means for converting the water in said well into hot moist vapor, and means for supporting an article of work in position to be treated by such vapor.

3. A treating apparatus comprising a flash-boiler, a water reservoir thermally insulated therefrom, and a pipe connecting them, the three said elements being arranged to maintain the water in equilibrium when the boiler is not functioning and the feeding capacity of said pipe being less than the vaporizing capacity of said boiler.

4. A treating apparatus comprising a flash-boiler, a water reservoir thermally insulated therefrom, and regulatable water-feeding means forming communication between said boiler and said reservoir, the three said elements being arranged to maintain the water in equilibrium when said boiler is not functioning, and the maximum feeding capacity of said means being less than the vaporizing capacity of the boiler.

5. A treating apparatus comprising an upstanding shell and an upstanding core therein forming a flash-boiler open at the top, said core being arranged to superheat hot moist vapor flowing upwardly in said boiler to work stationed over and adjacent to said top, heating means arranged in said core, and means arranged to supply water to said well at a rate slow enough to insure exposure of a considerable surface area of said core to the vapor generated in the lower part of said boiler.

6. A treating apparatus comprising an upstanding shell and an upstanding core

- therein forming a thin and relatively deep well open at the top and closed at the bottom, means arranged to supply water to said well normally to a relatively high level but 5 at a slow rate of flow, and means arranged to heat said core and thereby lower the surface of the water in said well below its normal level by vaporizing the water at a rate faster than the rate of replenishment afforded by said supplying means, thus decreasing the area of contact between said core and the water and increasing the area of contact between said core and the vapor flowing upwardly in said well.
- 15 7. A treating apparatus comprising means forming an open-topped well, a reservoir for cold water, a conduit forming communication between said reservoir and said well, said conduit, said means and said reservoir 20 being arranged to maintain the water normally in equilibrium in all of them, an upstanding core in said well, and heating means arranged in said well to vaporize the water therein and to superheat the vapor 25 flowing upwardly in the well, said conduit and said heating means being proportioned to lower the surface of the water in said well below the level of the water in said reservoir and thereby expose to the vapor a 30 portion of said core normally submerged in the water.
8. A shoe-treating apparatus comprising an open-topped upstanding tubular shell and an upstanding core therein forming a 35 substantially annular flash-boiler, a reservoir for water, a conduit arranged to supply water by gravitation from said reservoir to said boiler, said reservoir, said boiler and said conduit being arranged to maintain the 40 water in equilibrium when the boiler is not functioning, and heating means arranged in said core to reduce the water in said boiler below its level of equilibrium and thereby cause the boiler to operate as a flash-boiler.
- 45 9. A treating apparatus comprising an upstanding cylindric water receptacle open at the top and having an upstanding cylindric heat-radiating core by which the water-space is restricted to tubular shape, means 50 for supplying water to said space to be converted into vapor by said core, and heat-radiating means above said receptacle formed and arranged to spread the vapor laterally and having holes through which 55 the vapor may rise to work stationed above it.
10. A shoe-treating apparatus comprising a hollow metallic structure forming a vapor chamber and having a chamber to receive a 60 heating element, a water receptacle adjoining and depending from the bottom of said chamber, said receptacle having a metallic core projecting upwardly from its bottom, said core having a chamber for a heating 65 element to vaporize the water, and said

structure having one or more holes to emit the vapor to work stationed adjacent thereto.

11. A vapor-generating apparatus comprising a metallic upstanding heat-radiating element, an upstanding shell surrounding said element and forming a water-space also surrounding the latter and open at the top, means other than said upstanding element to heat said shell, and regulatable means for supplying water to said space to be vaporized by said element.

12. A vapor-generating apparatus comprising an upper heat-radiating element, a lower heat-radiating element, tubular means connecting said elements, said means surrounding said lower element and forming a tubular water-space of which said lower element forms an upstanding core, and means for supplying water to said space to be vaporized by said lower heat-radiating element.

13. A vapor-generating apparatus comprising an upper heat-radiating element, a metallic tube depending from and supported by said element, a heat-radiating core supported by and surrounded by said tube, said shell and core forming an annular water-space open at the top, and means for supplying water to said space to be vaporized by said core.

14. A vapor-generating apparatus comprising an upper heat-radiating element, a lower heat-radiating element, a metallic tube in heat-conducting relation to each of said elements, said tube and said lower heat-radiating element being formed and arranged to provide an annular water-space, and means to supply water to said space to be vaporized.

15. A vapor-generating apparatus comprising means forming an annular, upstanding boiler, a heat-conducting element supporting said boiler and engaging the outer wall thereof, means for heating said element, and means for supplying water to said boiler.

16. A vapor-generating apparatus comprising an upright, metallic tube, heating means in heat-conducting relation to the outside of said tube, heating means arranged in said tube to form an annular water-space, and means to supply water to said space to be vaporized.

17. A vapor-generating apparatus comprising a boiler open at the top to emit vapor, means for heating said boiler, means formed and arranged to spread the vapor laterally above the top of said boiler, and heating means arranged to heat said vapor-spreading means, a portion of the latter said means being in heat-conducting relation to said boiler.

18. A vapor-generating apparatus comprising heating means, an upright metallic tube suspended from said means and engag-

ing the latter in heat-conducting relation, and heating means arranged in said tube and joined to the lower portion thereof to be supported thereby, the latter said means and said tube forming an annular water-space.

19. A vapor-generating apparatus comprising a metallic supporting structure having a chamber for water, a metallic heat-radiating structure, metallic means rigidly connecting said two structures to support the latter and formed to minimize the con-

duction of heat, a metallic tube depending from and supported by said heat-radiating structure, a heat-radiating core arranged in and supported by said tube, said core and 15 tube forming a tubular water-space surrounding the core, and means for conducting water from said chamber to said water-space to be vaporized by said core.

In testimony whereof I have signed my 20 name to this specification.

FREDERICK M. FURBER.
